A. BEVAN

EGG BEATER

Filed Feb. 24, 1920

Inventor
Alexander Bevan.

By
Howard E. Garlow
Attorney.

UNITED STATES PATENT OFFICE.

ALEXANDER BEVAN, OF PROVIDENCE, RHODE ISLAND.

EGG BEATER.

Application filed February 24, 1920. Serial No. 360,633.

To all whom it may concern:

Be it known that I, ALEXANDER BEVAN, a citizen of the United States, and resident of the city of Providence, in the county of Providence and State of Rhode Island, have invented certain new and useful Improvements in Egg Beaters, of which the following is a specification.

This invention relates to egg beaters, and 10 has for its object to provide an improvement in this class of beaters in which two beater members are employed to rotate in opposite directions about a common axis, the beating surfaces of the beater members 15 being so disposed as to be readily accessible to be cleaned and so kept sanitary.

The nature and advantages of the invention will be better understood when the following detail description is taken in connection with the accompanying drawings, the invention residing in the combination and arrangement of parts as claimed.

In the drawings forming part of this specification, like numerals of reference indicate 25 similar parts in the several views and wherein:

Figure 1 is a side elevation of my improved beater.

Figure 2 is a detail of the outer frame 30 supported in its bearing member.

Figure 3 is an end view of the beater frame bearing member.

Figure 4 is a side elevation of the driving shaft and the inner beater members connected thereto.

It is found in the practical use of egg beaters that the beater members are pivoted at their lower ends to a frame or the like this pivot forms a stop or barrier and so 40 prevents or interferes with the ready and perfect cleaning of the working portions thereof and when the material into which the beater is inserted, is not entirely removed it decomposes and so renders the device unsanitary.

To obviate this objectionable difficulty I have so constructed my improved beater that the beater members are supported only at their upper portions above their beating surfaces; their lower or working portions being spaced from the frame and from each other to permit unhampered cleaning between them.

The following is a detail description of 55 one form of device adapted to perform the

functions of my invention, in which 10 designates the frame portion thereof which is preferably constructed of wire having two side members 11 spaced apart and set parallel with each other for a portion of their length, to form a handle portion 12, the lower portion 13 of this frame being enlarged to inclose the beaters, and the lower cross-bar 14 of which is adapted to rest upon the bottom of the receptacle in which 60 the material to be beaten, is held.

The sides of the frame are held in spaced apart relation by means of upper and lower bearing cross-bars 15 and 16 and are bound together by means of the binding plates 17, 70 the side edges 18 of which are rolled over said side frames.

In these bearing bars is mounted a vertically-disposed driving shaft 19, its upper end being provided with a driving pinion 20, 75 and its lower end with a coupling or sleeve 21 into which the upper end of the smaller or inner beater frame member 22 is fixed so that this beater member is caused to rotate in unison with this shaft.

Loosely mounted on this shaft above this coupling member is a bearing member or hub 23, its upper end being provided with a driving gear 24 and the body portion of this bearing member is slotted longitudinally at 25 on opposite sides to receive the spaced apart side arms 26 of the wire outer beater frame 27.

These arms are preferably indented as at 32 to fit into corresponding recesses 33 in 80 the slots 25 and when these arms are positioned in these slots they are locked therein by a collar or ferrule 28 which is forced over the same about the bearing member to bind and releasably secure these arms in 85 their slots; it being only necessary to remove this ferrule when it is desired to detach this frame from its hub.

In order to impart a rotating motion to the shaft 19 and its inner beater frame 22 100 in one direction, and the bearing member 23 with its outer beater frame in the opposite direction, I have mounted a large driving gear 29 on the pin 30 in the binding plate 17, which gear is provided with a suitable handle 31 by which it may be rotated.

By this construction it will be seen that the inner and outer frame-shaped beater members are mounted to rotate one within the other both about a common axis and 110

that both of these beater members are separated from each other at all points and are also separated from the frame which encloses them, whereby no obstacle is offered to the free passage of a cleaning member all around between the beater members and the outer supporting frame. No lower pivot or bearing being provided to prevent such cleaning action.

10 In some cases instead of making the side members of the wire beating frames straight, as illustrated in Figures 2 and 4, I so bend the sides of these frames inwardly as at 34 and 35, that they will interlock one with the other thereby rendering more effective the beating action.

My improved device is extremely simple and practical in construction and effective in its operation and by the improved arrangement of its parts it may be readily and thoroughly cleaned thereby rendering it perfectly sanitary.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An egg beater comprising a supporting frame forming a handle at its upper end and a rest at its lower end, upper and lower bearing-bars detachably secured to said frame, a driving gear, a driving shaft mounted in said bearing-bars, a pinion on said shaft engaging said driving gear, an inner beater frame, a coupling connecting said beater frame to said shaft, a bearing member rotatably mounted on said shaft between said coupling and said lower bearing-bar and retained from longitudinal movement thereby, a pinion on said rotatable bearing member engaging said driving gear, and an outer beater frame supported on said rotatable bearing member whereby said

beater frames are rotated in opposite directions.

2. An egg beater comprising a supporting frame, upper and lower bearing-bars fixed to said frame, a driving shaft mounted in said bearing bars, a single bearing member rotatably mounted on said shaft, means for preventing relative longitudinal movement of said shaft and bearing member, a wire beater frame supported upon and driven by said rotatable bearing member, means for releasably locking said beater frame upon said rotatable bearing member, and a second wire beater frame supported upon and driven by said shaft, the lower parts of said beater frames being unsupported and spaced apart.

3. An egg beater comprising a wire supporting frame bent to form a handle, a body portion, an enlarged beater frame encircling base portion, bearing cross bars supported on said body portion above the beating action, a shaft provided with a pinion at its upper end rotatably supported in said bars and prevented from downward movement by one of said bars, an inner beater frame formed of wire, a coupling connecting said inner frame and shaft, a sleeve provided with a pinion gear rotatable on said shaft and supported by said coupling, said sleeve being provided with recesses, an outer wire beater frame spaced from the inner frame and having arms engaging said recesses, a removable ferrule for detachably binding said arms in said recesses each of said frames being wholly unsupported at its lower end, said beater frames and supporting frame when in normal position and in substantially the same plane nesting one within the other, and a driving gear rotatably supported by said body portion meshing at diametrically opposite points with each of said pinions whereby when said gear is rotated the said beater frames will rotate oppositely one about the other.

In testimony whereof I affix my signature.
ALEXANDER BEVAN.
